LONGITUDE POSITION FINDER

Ernest Kloht, New York, N. Y.

Application July 14, 1933, Serial No. 680,363

3 Claims. (Cl. 33—1)

The main object of this invention is to provide a device for accurately determining the longitude location of a ship, of which the device is part of the equipment, when given the latitude.

5 Another object of the invention is to provide a device for locating and charting the longitude of a ship when the latitude and sun declination are given.

10 The above and other objects will become apparent in the description below, in which characters of reference refer to like-named parts in the drawing.

Referring briefly to the drawing, Figure 1 is a front elevational view of the finder.

15 Figure 2 is a side elevational view of Figure 1. Figure 3 is a top plan view of Figure 1.

Figure 4 is a cross sectional view through one of the sectors showing the means for locking the vernier carriage in place.

20 Figure 5 is a bottom plan view of two cooperating sectors showing their relation.

Referring in detail to the drawing, the numeral 10 indicates a flat semi-circular half ring over approximately one half whose face arcuate graduations from 0 degrees to 80 are graduated and are indicated by the numeral 11. The zero graduation 12 is located centrally on the ring. The ends of the half ring 10 are squarely recessed at 13 as shown in Figure 3. On one side of the cut-out portions 13 the face of the ring ends 10 has tapering surfaces 14 which permit the folding over to a 15 degree angle of a cooperating semi-circular sector 15. The open ends of the sector 15 are recessed at 16 so as to match the ends of the ring 10. The ends of the sector 15 and ring 10 are mutually pivoted to each other by pins 17 in such fashion as to permit the sector 15 to swing to a position super-imposed over the ring 10. This sector is graduated over its entire face, the graduations 18 increasing on both sides of the zero graduation 19 which occurs at the centre of the sector.

Aligned with the zero graduation 12 one end of an arc 20 is removably fixed to the inner marginal edge 21 of the ring 10 and rises arcuately from the latter. The opposite end of the arc 20 is adapted to slidably pass through a rectangular open channel 22 formed in the inner marginal edge 23 of the sector 15. Adjacent one side of the channel a tapering pocket 25 is formed. The intersection of the pocket and channel is at the center of thickness of the sector and the reading of the graduations is made from this position. The graduations occur on one face of the arc 20 and are indicated by the numeral 24. A curved

vernier 26 is mounted on the inner edge 23 of the sector 15 and is deformed to lie flat upon the graduated face 27 of the arc 20.

An altitude arc 28 cooperates with the remaining members and has graduations 29 from zero 5 30 to 90 degrees near the lower end and from zero to 20 degrees at the upper end. The lower curved end of this altitude arc is pivotally secured to a vernier carriage 31 by a pin 32. The carriage 31 is provided with a vernier blade 33 upon which 10 graduations 34 are inscribed. A locking carriage 35 is coupled to the vernier carriage 31 by a threaded adjusting screw 36 which latter engages both the vernier and locking carriage. The adjusting screw has a knurled enlargement 15 37 thereon which is engaged by the fingers when adjustment is to be made.

The sector 15 has a vernier carriage 38 thereon which is adjustably coupled to a locking carriage 39 by an adjusting screw 40. Said vernier carriage 38 is coupled pivotally to a second vernier carriage 41 which latter rides on the inner edge 20 of the altitude arc 28 and said vernier carriage is equipped with a locking carriage 42 and adjusting screw 43. The carriage 38 and 41 are 25 pivotally coupled by a hinge pin 44.

On the reverse sides of the altitude arc 28, ring 10 and sector 15, arcuate channels 45 are formed. All of the vernier and locking carriages are provided with keys 46 which are integral 30 with their related parts and register in the channels 45. All of the locking carriages 35, 39 and 45 have threaded apertures 47 in which the threaded shanks 48 of knurled locking screws 49 are inserted.

35 The device is adapted to determine the longitude in which a ship is located at the time of reading. For example: by setting the carriage 33 at 42 degrees 26 minutes N. and setting the vernier 41 at 13 degrees 44 minutes on the graduations on member 24, and setting the vernier 38 at 17 degrees 58 minutes south, the reading on the arc 20 will be 49 degrees 34 minutes, which will indicate the longitude of the ship. The 40 graduations on arc 20 register longitude, altitude arc 28 registers the altitude of the sun, ring 10 registers the latitude and sector 15 indicates the declination.

45 It is to be noted that certain changes in form and construction may be made without departing 50 from the spirit and scope of the invention.

I claim:

1. A semi-circular flat band, a semi-circular declination sector, said band and sector being graduated and mutually hinged, said band hav- 55

- ing its hinged ends tapered for swinging declination sector to a fifteen degree angle, a graduated altitude arc movably joined to said band and rising above said sector, a pivotally joined pair of verniers engaging said altitude arc and sector, a vernier carriage riding on said band having said altitude arc pivotally secured thereto and means for guiding and locking said verniers on said cooperating members.
10. 2. A semi-circular flat band, a semi-circular declination sector, said band and sector being graduated and mutually hinged, said band tapering at the outer corners to adapt the declination sector to swing to an angle of fifteen degrees with respect to said band, a graduated altitude arc movably joined to said band and rising above said sector, a pivotally joined pair of verniers engaging said altitude arc and sector, a vernier carriage riding on said band having said altitude arc pivotally secured thereto and a curved channel on said band, sector and altitude arc for
- 15
- 20

guiding said verniers around said cooperating members, and means for locking said verniers in any desired position.

3. A semi-circular flat band, a semi-circular declination sector, said band and sector being graduated and mutually hinged, a graduated altitude arc movably joined to said band and rising above said sector, a pivotally joined pair of verniers engaging said altitude arc and sector, a vernier carriage riding on said band having said altitude arc pivotally secured thereto and a curved channel on said band, sector and altitude arc for guiding said verniers around said cooperating members, locking carriages engaging said sector band and altitude arc and partly registering in said channels, locking screws for securing said carriages, and vernier adjusting screws engaging said verniers and carriages to adjust the former.

ERNEST KLOHT. 20
